UNITED STATES PATENT OFFICE.

McCLINTOCK YOUNG, JR., OF FREDERICK, MARYLAND.

IMPROVEMENT IN REAPING AND MOWING MACHINES.

Specification forming part of Letters Patent No. 30,276, dated October 2, 1860.

To all whom it may concern:

Be it known that I, MCCLINTOCK YOUNG, Jr., of the city and county of Frederick, and State of Maryland, have invented certain new and useful Improvements in Reaping and Mowing Machines; and I do hereby declare that the following is a full, clear, and exact description of the construction and operation of the same, reference being had to the accompanying drawings, in which—

Figure 1 represents a perspective view of a mowing-machine. Figs. 2, 3, 4, and 5, represent detached views, hereinafter to be referred to.

My invention relates to the combination of certain devices for the purpose of connecting or disconnecting the cutting apparatus to or from the gearing of a harvesting-machine.

To enable others skilled in the art to make and use my invention, I will proceed to describe its construction and operation.

A represents the frame of the machine. It is hung by means of the journal-boxes B to the main driving shaft or axle C, which is supported in the driving-wheels D D', which latter is firmly secured to said driving-shaft, while the former is fast and loose, as occasion may require. The bevel-wheel E is rigid on the axle or driving-shaft C, within or close to the wheel D. It meshes into the pinion F on the shaft I, to which the crank-wheel H is connected, that vibrates the cutter-bar.

G represents a clutch-lever, which is pivoted at s to the side of the wheel E. Its position in relation to the circumference of the wheels E and D is not a radial one, but that of the chord of the arc of said wheels, and the oblique or curved end of the lever G is pressed toward the inner circumference of the rim a of the wheel D by means of a spiral spring, b, the end of which passes through said lever at c, so that when the machine is moved forward, or when the driving-wheels turn in the direction of the red arrow, Fig. 2, the rim of the wheel D presses on the clutch-lever G and thus clutches the wheel D with the bevel-wheel E, causing them to turn together, and consequently operate the pinion F and the cutting apparatus. Upon the machine being backed, or the wheel D being turned in the direction of the blue arrow, the rim of the driving-wheel D slips over the oblique end of the

lever G, unclutching itself from the bevel-wheel E, continues to turn, but without moving the bevel-wheel, and hence the cutting apparatus is not operated. If the cutting apparatus is to be disconnected from the machine, the lever G is set in the position represented in Fig. 3, the end c of the spring, which forms a stud or projection, being raised up and supported by the shoulder on the spring d, whereby the end of the lever G is disconnected from the rim of the driving-wheel D, and the wheel can then turn freely on the axle C forward, without acting as a driving-wheel to any of the moving parts of the machine. The crank-wheel H is set loosely on the shaft I, that carries the pinion F; but the ratchet f, being secured to the shaft I, bears against the pawl g of the wheel H when the shaft I is turned, and causes the crank-wheel H to turn with the shaft. The pawl g can be disengaged from the ratchet f by turning it on its pivot 1, and it is held in that position by the pressure of the spring h on its end 2, which spring also holds it in gear with the ratchet, and in that position the crank-wheel H, and consequently the cutting apparatus, remains stationary when the machine is moved even forward. The finger-bar K is secured to the finger-bar plate L by means of the screws 3, and the plate L is hinged to the shaft M, and can freely turn thereon; or it may be secured to said shaft, and in that case has to turn with said shaft when the finger-bar is raised or lowered.

The lever N, for raising or lowering the cutting apparatus, is secured directly to the plate L, and the driver on his seat O can operate it with facility; and as in this arrangement no part of the frame is connected to said lever which has to be moved when the position of the cutting apparatus is to be adjusted, but only the weight of the cutting apparatus and of the plate L, the work of the operator is greatly facilitated by the direct application of his lever to the finger-bar or finger-bar plate.

The sickle-bar P is connected with the crank-wheel H by the pitman Q, and the connection between the pitman and the wheel H is made by means of a ball-and-socket joint, as represented in Figs. 1 and 4, the ball l being secured to the stem or wrist-pin m, while the end of the pitman is provided with a socket or

cups, *n*, which are composed of two segments secured together by the bolts *o*. The pitman *Q* is connected to the cutting apparatus also by means of a double hinge, the bent end of said pitman being inserted within the eye *p*, and the shank *q* of said eye being secured to the sickle-bar by a bolt, *r*, on which it can freely turn, thus producing a universal motion. These connections, in combination with the ball-and-socket joint above described, allow of the perfect working of the entire machine in any position to which the cutting apparatus may be adjusted.

When the machine is used for reaping, the cutting apparatus may be secured rigidly to the frame by means of a chain or rope, *u*, one

end of which is secured to the stiff pole *S*, while the other end may be hung to the hook *R* of the lever *N*.

Having thus fully described the nature of my invention, what I claim as new, and desire to secure by Letters Patent, is—

The combination of the self-acting spring-clutch lever *G*, with the loose driving-wheel *D* and fast gear-wheel *E*, for making a self-acting clutch, substantially in the manner and for the purpose herein described.

McCLINTOCK YOUNG, JR.
